BRACE FOR SUPPORTING LIDS OF DISPLAY CHESTS

James J. Hogan, Meriden, Conn., assignor to The International Silver Company, Meriden, Conn., a corporation of Connecticut

Application March 1, 1952, Serial No. 274,452

5 Claims. (Cl. 217—61)

This invention relates to a brace for supporting the cover or lid of a display chest in raised position. More particularly, the device is intended for use in chests of the type used for the display of silverware and the like.

Display chests for silverware and the like generally comprise a body portion for containing some of the articles and also a lid portion hinged thereto for displaying other articles. The hinge is adapted to permit display of the contents contained on the inner side of the lid by swinging the lid to an upstanding position at the rear of the body portion.

The hinge is usually of light construction as two small butt hinges spaced on the rearmost edge of the body portion. The movement of the lid is restricted as by a tape or web formed from the inner lining material of the chest. The web or tape is attached to the inside of the lid and to the base and normally prevents the former from falling to a rearward horizontal position. Inasmuch as the contents on the lid of the chest are of a relatively heavy nature in comparison with the hinge construction the tape is generally designed to hold the lid balanced rearwardly to a very slight degree only, which prevents strain on the web and holds the lid in a raised position for display purposes. While this construction is effective for an attractive display it does however create difficulty in handling the chests when opening the same or handling the contents. A slight jarring movement will often result in the lid inadvertently falling shut.

Furthermore, chests of silverware are frequently arranged on stands in store windows or in the stores themselves with the back edge of the chest raised so that passersby, in looking at the merchandise, can more easily observe the entire contents of the open chest. Such a display arrangement creates the problem of providing means to keep the lid of the chest securely raised in an open position.

One object of the invention is to provide means to hold the lid of a display chest open when the back edge of the chest is raised and the lid open to reveal the contents for display purposes.

A further object is to provide a novel brace for easy application to a chest of this general type when resting on a flat surface so as to maintain the lid in raised open condition and relieve the strain on the webbing under a tendency of the lid to fall rearwardly.

These and other specific advantages of the invention will be appreciated from the following disclosure in conjunction with the accompanying drawings, in which,

Fig. 1 is a fragmentary perspective view of one end of a chest with the new brace holding the lid in vertical raised position;

Fig. 2 is a detail view of the brace on a larger scale and apart from the chest and lid of Fig. 1;

Fig. 3 is a view from the top of Fig. 2 illustrating in dotted line various relative positions of the two wedge members of the brace; and

Fig. 4 is a side elevation of a modified structure of the brace holding a lid in open position.

2

In Fig. 1 the body of the chest is shown with a side wall 1 having a top edge 2 and a rear wall 3 along which the lid 4 of the chest is hinged at each end as at 5. The lid 4 is substantially a duplicate of the base with front, rear, and side walls at 6, 7, and 8 respectively.

In the base of a display chest such as is used for silverware most of the implements are stacked for display in the slots of a rack 9. In the cover loops 10 are commonly provided to hold other implements such as knives. The 10 interior of the base and the lid is also provided with a cloth lining to retard tarnishing and the lining is extended above the inner edges of the side and front walls as the liner strip 11 to seal the contents from the atmosphere when the chest is closed for storage.

15 To limit the opening movement of the lid and to prevent its falling to a rearward horizontal position a tape or web of the lining material is fixed to the rear wall of the base and to the rear wall of the lid. The web along the section between these two rear walls is dimensioned to permit an opening movement of the lid to a vertical position best shown in dotted line in Fig. 4. When closed the cloth of the web along the hinge is folded on itself.

With the lid, when opened for display, being normally 25 in the dotted line position of Fig. 4 it will be seen that a very slight movement of the chest or its contents will tend to jar the lid and permit its falling to closed position. Where any force is applied to urge the lid rearwardly as is normally the case when the lid is weighted by its 30 contents, a strain is placed on the web. The bracing device of this invention is designed to relieve this strain entirely and to prevent the lid from falling either forwardly to a closed position or in a rearward direction to pull at the web and possibly tip the chest on the rear sidewall of the base.

As shown in the drawings the device comprises a pair of wedges 12 and 13 preferably in the form of blocks square in cross section and joined together by a rigid connecting member as a stiff wire 14. The device is 40 inserted as shown by Fig. 1 at the rear corner of the chest at the top of the rear wall 3. A similar brace is preferably inserted at the opposite side of the chest.

The position of the wedge blocks between the lid and base is best shown by Fig. 4. Block 13 rests with an 45 upwardly facing surface abutting the outer corner surface of the rear wall of the lid, and the adjacent inwardly facing surface abutting the upper corner portion of the rear wall of the base. Block 12 is positioned with a downwardly facing surface against the upper edge of the 50 adjacent side wall of the base and the adjacent outwardly facing surface of the block abuts the inner edge of the side wall 8 at the corner of the lid. The rigid wire 14 holds the blocks in spaced relation on each side of the hinge line.

55 In the detail plan view of Fig. 2 it will be seen that the wire 14 is U-shaped with the legs 15 at each end thereof carried by the blocks so that the bracing surfaces of the blocks are offset laterally from the wire. It will also be noted in Figs. 2 and 3 that the legs are mounted eccentrically of the axis of the blocks, the center lines thereof being indicated by lines *a* and *b*. The legs are pivotally mounted in the blocks in the preferred form of the device shown by these views and are held against removal therefrom by a friction fit. The blocks are also 60 preferably of hard wood of the same type as the wood of the usual display chests and may be provided with an identical finish. Such chests are most generally provided with a dark mahogany finish and the blocks may thus be set in place unobtrusively and blend with the finish of the chest. The blocks may be of course made of 65 other material such as plastic or metal.

The brace is simply and easily slid into place and

removed laterally at the hinge line when the lid is in open position. As shown by Fig. 4 in which the dotted line position of the cover represents the normal open position, a preferred spacing of the two blocks and insertion of the device causes the lid to be elevated to a more truly vertical condition. Thus even the normal strain imposed on the hinge web is relieved.

Referring again to Figs. 2 and 3 it will be seen that each block has oppositely facing surfaces and the surfaces of one block face in opposite directions to those of the other block. By reason of the eccentric pivotal connection of the legs of the U-shaped wire to the blocks, each block may be twisted on its leg 15 to provide a different spacing between the blocks. The dot-dash and dotted line positions of block 12, indicated by the numerals 16 and 17 respectively, illustrate by way of example two further adjustments in spacing. Since both blocks 12 and 13 are eccentrically pivoted there is a wide variation possible and a single brace may be used for different sizes of chests.

As a modification it will be noted in Fig. 4 that while block 13 is square, block 12 is rectangular, but in each case the leg of the wire is attached centrally. Thus, by rotating block 12 clockwise 90° from the position shown, the blocks would be adjusted for a chest having a shorter spacing across the hinge line. The leg on block 13 may or may not be pivotally fixed, as desired.

It is clear that if desired, both blocks 12 and 13 could be made rectangular, or that either or both legs could be mounted eccentrically.

What is claimed is:

1. A brace for supporting the lid of a display chest in raised position comprising a pair of wedge blocks square in cross section and a stiff wire member of U-shape having each leg thereof pivotally connected to one of said blocks on an axis eccentric thereto, said U-shaped member holding the blocks in spaced relation for placement of the blocks on opposite sides of the hinge line of a lid with one of said blocks wedged between the rear edge of said lid and rear wall of said chest and the other block wedged between the top edge of a side wall of the chest and the adjacent inner edge of the lid in open position.

2. A device for locking the hinged lid of display cases and the like in predetermined substantially upright position with respect to the case which comprises a pair of wedge members of six-sided block form each having a pair of oppositely disposed end walls, the side walls of each member having planar surfaces and any pair of adjacent sidewall surfaces of each member forming working surfaces at right angles to each other, any of said pairs of adjacent planar sidewall surfaces of one member being engageable against adjacent mating portions at the inner edge of the lid and the top of the opposed wall of

the case for preventing movement of the lid to closed position and any pair of said adjacent planar sidewall surfaces of the other member being engageable against the outer wall portion at the rear edge of said lid and the adjacent wall of the display case for preventing opening movement of the lid beyond said upright position with said members lying on opposite sides of the axis of the lid hinge, and a rigid connecting member pivotally attached at each end to a corresponding end wall of each member holding said members to a predetermined spaced relation for placement of said members at opposite sides of the hinge line of said case with a pair of said adjacent planar surfaces of each member in wedging engagement, said rigid member lying in laterally offset relation to said corresponding end walls, and said pivotal end connections to said end walls being within the boundaries thereof and on axes parallel to said side wall surfaces.

3. The structure of claim 2 in which said rigid connecting member is a U-shaped wire rod having each leg thereof frictionally pivoted in the body of said wedge members and at least one of said pivotal leg connections being on an axis eccentrically disposed in the end wall of said wedge.

4. The structure of claim 2 in which said rigid connecting member is a U-shaped rod and the end wall of at least one of said wedge members is in the form of a rectangle having sides of unequal dimensions and the pivotal connection of said rod thereto is on the central axis of said rectangular end wall.

5. The structure of claim 2 in which one of said wedge members is in the form of a rectangle having sides of unequal dimensions and the pivotal connection of said rod thereto is on the central axis of said rectangular end wall and the other wedge member is formed with a square end wall with the said pivotal connection of the rod thereto on the central axis thereof.
